(57) **CLAIM**

The ornamental design for a tire tread, as shown and described.

DESCRIPTION

FIG. 1 is a front elevation view of a tire tread, of which the rear elevation, top plan and bottom plan are identical; FIG. 2 is a left elevation view thereof, of which the right elevation is identical;

FIG. 3 is a top perspective view thereof;

FIG. 4 is a close-up front elevation view thereof;

FIG. 5 is a close-up left elevation thereof; and,

FIG. 6 is a close-up top perspective view thereof.

The broken lines in the figures are for the purpose of illustrating unclaimed portions of the article and form no part of the claimed design.
